UNITED STATES PATENT OFFICE.

SAMUEL W. JONES AND BENJAMIN D. EVANS, OF NELSONVILLE, OHIO.

IMPROVEMENT IN EAVES-TROUGH HANGERS.

Specification forming part of Letters Patent No. **147,329**, dated February 10, 1874; application filed January 17, 1874.

To all whom it may concern:

Be it known that we, SAMUEL W. JONES and BENJAMIN D. EVANS, of Nelsonville, in the county of Athens and State of Ohio, have invented a new and Improved Eaves-Trough Hanger, of which the following is a specification:

In the accompanying drawing, Figure 1 represents a top view of our improved eaves-trough hanger, and Figs. 2 and 3 side views of the same.

Similar letters of reference indicate corresponding parts.

The object of our invention is to provide a cheap, strong, and easily applied hanger for eaves-troughs, by which they may be firmly and conveniently attached to and suspended from the roofs of houses. Our invention consists of splitting and twisting a piece of hoop-iron of suitable strength, and attaching the twisted ends to the eaves-trough, while the main piece is applied to the roof at a suitable inclination.

In the drawing, A represents the hanger; B, the eaves trough or gutter attached thereto. The hanger A is made of hoop or band iron, which is split in two parts, C, at one end, which parts C are twisted, as shown in the drawing,

and soldered, riveted, or otherwise attached, by their outer ends, to the eaves-trough, suspending the same freely and securely thereby. The upper unsplit part of hanger A is bent at a suitable inclination toward the roof, as required by circumstances, and is then firmly attached to the roof or other part of the house along which the trough runs.

The twisting of the hoop ends strengthens and stiffens the same, increasing in the manner of corrugations the resistance to the strain exercised thereon, and forming a neat, cheap, and readily applied attachment for supporting eaves-troughs.

Having thus described our invention, we claim as new and desire to secure by Letters Patent—

The improved eaves-trough hanger, made of hoop-iron of suitable strength, which is split at one end, and twisted and attached to the trough, while the upper end or main part is applied at a suitable inclination to the roof, in the manner substantially as specified.

SAMUEL W. JONES.
BENJAMIN D. EVANS.
